HUGO LENTZ, OF BERLIN, GERMANY.

TURBINE-ENGINE.

No. 846,928.

Specification of Letters Patent.

Patented March 12, 1907.

Application filed March 31, 1905. Serial No. 253,112.

To all whom it may concern:

Be it known that I, HUGO LENTZ, a subject of the German Emperor, residing at 10/11 Potsdamerstrasse, Berlin, Germany, have invented a new and useful Improvement 5 in Turbine-Engines; and I do hereby declare the following to be a full, clear, and exact description of the same.

This invention relates to turbine-engines; 10 and its objects are, first, to provide a turbine-engine in which the power-wheel or power-wheels may be run in either direction; second, to provide a turbine-wheel of novel construction and useful in such form of engine; third, 15 to simplify the manufacture of turbine-wheels, especially referring to the aforesaid novel form, and, fourth, to provide a turbine-engine which shall be simple in construction and economical in operation.

20 Prior to my invention it has been proposed to construct turbine-engines, whether driven by steam, gas, or water, with impact-wheels which could be driven in either direction by the pressure medium. So far as I am aware, 25 however, all of said prior or proposed structures have required the driving of one or the other of two impact-wheels mounted on or connected with either one or two power-shafts to drive the same in one direction or 30 the other or the connection of two independent sets of paddles with a single impact-wheel and intended for driving the same in opposite directions. It is always, of course, possible with a turbine-wheel having impact-surfaces inclined or recessed in one direction 35 only to project the pressure medium against either the impact-faces or against the non-impact faces, and consequently reverse the motion of the wheel to some degree, but with 40 a prohibitive consumption of pressure medium. One proposed structure required the employment of separate oppositely-rotatable turbine-wheels with corresponding shafts. Other proposed forms have called for two 45 such rotatable turbine-wheels upon the same shaft. (See in this connection page 315 of Loewenstein's translation of the second edition of *The Steam Turbine*, by Stodola.) Where two turbine-wheels have been em- 50 ployed, they have usually been fixed near each other or arranged to be telescoped or housed one within the other. With any of such constructions, however, it has been necessary to drive two wheels, one of which does 55 no work and retards the efficiency of the other by offering resistance to the air. In

the turbine later proposed and which required two sets of paddles (one for forward rotation, the other for reverse rotation) applied to a single wheel this same difficulty is 60 present.

My present invention contemplates the use in a turbine-engine of an impact-wheel which is provided with peripheral paddles having recessed impact-faces which permit 65 the wheel to be driven with great facility in either direction. As shown in the drawings and as hereinafter described, I prefer that the paddles shall be thicker than the usual forms of turbine-blades, shall have impact- 70 recesses at both sides of each paddle, and shall be integral with the rim portion of the wheel.

Referring to the drawings, Figure 1 is a cross-sectional view of a form of turbine-engine embodying my present improvements and showing my improved turbine-wheel and the nozzles for supplying pressure medium to drive the wheel in either direction. Fig. 2 is a sectional view showing a fragment of my 80 new turbine-wheel. Fig. 3 shows a turbine-wheel devised by me and carrying guiding devices to assist the action of the pressure medium upon the blades or paddles. Figs. 4, 5, 7, 8, 9, and 10 show various forms and 85 relative arrangements of blades or paddles according to my invention. Fig. 6 shows a nozzle for directing pressure medium to the blades or paddles and a channel for returning and reusing the pressure medium after it has 90 once left the wheel.

As seen in Fig. 1, *e* and *f* indicate the opposite nozzles injecting pressure medium against the opposite impact-faces *a* and *b* of the paddles or blades of the turbine-wheel 95 and in the direction indicated by the arrows. It will be understood, of course, that but one nozzle is operating at a time. The turbine-wheel is arranged between the two nozzles, as shown, and by this arrangement I am able to 100 provide a turbine-engine having a single wheel adapted to run in either direction and to correspondingly drive a power-shaft (not shown,) a form of engine particularly well adapted for marine work.

105 The form of turbine-wheel preferably employed by me in the illustrated turbine-engine is provided with blades or paddles having recessed or concave impact-faces *a* in one direction and with blades or paddles having recessed or concave impact-faces *b* in an opposite direction, thus permitting either set

of impact-faces (*a* or *b*) to be exposed to the action of the supplied pressure medium. As shown in the drawings, the blades or paddles are preferably each made of a single piece or block as distinguished from that compound or built-up form of paddle or blade consisting of two curved plates secured in place by a bridge or stay and which has been quite expensive to manufacture. It will be obvious that the paddles or blades may be integral with the wheel or its rim portion or may be attached or applied thereto in any of the ways well known in this art.

As shown in Figs. 1, 3, 4, 7, 8, 9, and 10, the curvature of each of the concave impact-faces *a* and *b* is bounded by a straight line, which is substantially parallel with an imaginary line *m n*, passing through the blade, as indicated in Fig. 4. If desired, however, the curvature of each of the impact-surfaces may be bounded by a line which slopes toward the imaginary line, as shown in Figs. 5 and 6.

By reference to all of the figures, excluding Fig. 4, it will be seen that I may slope the blade edges or sides *c* and *d* either in the same or opposite directions. Where, as especially shown in Fig. 5, the parts *c* and *d* are sloped in parallelism and which correspond with the relative flow direction, not only are impulse losses minimized or avoided, but a paddle or blade is provided which is advantageously acted upon by pressure medium when returned by a deflecting chute or way *g* (see Fig. 6) to the turbine-wheel. It may be preferred, however, as shown in Figs. 7 and 8, to provide the paddles or blades with sloping edges *c'* and *d'*, which incline toward each other, and thus avoid or minimize any unfavorable angles or surfaces which might otherwise be presented to the pressure medium delivered through a deflecting-chute, such as *g*. The curvatures *a'* and *b'* may be identical, Fig. 7, or varying, Fig. 8, to suit the desired purposes. Thus the general relation of the corresponding parts of the curvatures is $-r$, may be larger, equal to, or smaller than r^2 .

The forms of blades shown in Figs. 7 and 8 are particularly advantageous for repeated steam inflow in the direction of movement to the right, while the relations for the opposite direction of movement are less favorable. In practice I prefer that the more advantageous form of blade (having curvature *a'*) be taken for the forward rotation, while the other or smaller form (having curvature *b'*) be reserved for backward rotation. If desired, however, the two forms of curvature may be alternated, as shown in Figs. 9 and 10.

As shown in Fig. 3, a guide-piece *k*, which may be hollow or be a solid block, as illustrated, may be inserted between each pair of blades and will assist in deflecting the jet of

pressure medium against the curved impact-faces. The guide means may be integral with or added or attached to the wheel or its rim portion.

I prefer that the paddles or blades may be integral with the rim portion of the wheel, and any of the various forms of paddles or blades shown in the drawings may be formed in the wheel-rim by cutting radially thereinto by means of a conical drill or any other suitable tool, such as a countersink, slide-rest tool, or the like. As shown diagrammatically in Figs. 9 and 10, a suitable size of drill may be used and the opposite impact-faces of successive paddles or blades be cut simultaneously. Obviously the paddles or blades and the guiding means *k* may be formed simultaneously with suitable tools.

The method of manufacture, by which two blades are simultaneously provided with adjacent and oppositely - recessed impact-surfaces, constitutes the subject-matter of an application filed as a division of this present case.

What I claim is—

1. In an elastic-fluid turbine, a rotatable element having a plurality of symmetrically-curved buckets each provided with two similar concave impact-surfaces facing in opposite directions, the adjacent impact-faces of successive buckets being oppositely disposed in the plane of rotation of said element, and means to discharge fluid-pressure against said buckets to rotate said element.

2. In an elastic-fluid turbine, the combination with a rotatable element adapted to be driven in opposite directions by the impact of fluid-pressure, of a plurality of buckets or blades whose front and reverse faces are concaved and whose side edges are parallel and angularly disposed to the plane of rotation of the element.

3. In a turbine, a rotatable element carrying buckets or blades formed with two impact-surfaces which face in opposite directions, said buckets increasing in thickness from the center toward the side edges, an impact-surface and side edge of one bucket standing opposite to the reversely-facing impact-surface of an adjacent bucket.

4. In a turbine, a bucket element formed with two wide arcuate impact-faces of substantially equal surface area which face in opposite directions and are arranged in staggered relation to each other, and narrow parallel sides connecting the corresponding edges of said faces.

In testimony whereof I have signed my name to this specification in the presence of two subscribing witnesses.

HUGO LENTZ.
